UNITED STATES PATENT OFFICE.

RICHARD SPRENGER AND HERMANN CONRADT, OF HENNINGSDORF, GERMANY, AS
SIGNORS TO GENERAL ELECTRIC COMPANY, A CORPORATION OF NEW YORK.

SUCTION DEVICE FOR MICA COATING MACHINES.

Application filed October 17, 1925, Serial No. 63,157, and in Germany January 9, 1925.

Our invention relates to mica coating machines and the like, and has for its object the provision of suction apparatus whereby a high holding force is obtained and the entrance air limited when the suction orifices are uncovered.

The manufacturing of plates from split mica is carried out by the individual thin sheets of mica being laid in single layers near each other and overlapped. On the layer there is placed an adhesive substance, then another layer is laid on and so on until the desired strength of the plate has been obtained. The manufacture of insulating paper stuck with thin sheets of mica is carried out in the same manner. Hitherto the individual layers have been laid on by hand; it has, however, often been tried to form the thin sheets of mica and put them into layers mechanically. For this a vacuum was usually used. In the case of devices worked by hand, a hollow suction head was provided which was connected with an exhauster or an air pump, and which had an even perforated plate or wire gauze. In mechanical arrangement, the suction plate has, amongst other things, the form of a rotating cylinder.

The results obtained with such suction devices were not, however, satisfactory. The thin mica sheets are so often telescoped that the greater number cling together and as a whole remain stuck to the suction neck even when only one or two sheets are caught in front of the suction aperture. In order to effect a covering of the neck only by placing a sheet in front from time to time, brushes are arranged which brush away the superfluous sheets. In this case, however, when the partial vacuum in the neck or the suction aperture was not great enough all the sheets were dragged from the apertures.

In order to overcome this drawback as much as possible the suction apertures were made as large as possible as with the use of exhausters the degree of vacuum was limited. In practical working all apertures cannot be covered by sheets but frequently a great part of them will not be covered. Through these apertures there then enters such a large quantity of air that the vacuum in the neck drops to such an extent that the

sheets in front of the other openings are no longer held fast enough.

If, in spite of this, a sufficiently high vacuum had to be maintained, then the ventilator or the air pump had to be made so large that the necessary expenditures in power made an economical working impossible.

As is known the force with which a sheet is pressed and securely held in front of an aperture by air pressure is

$$F = A \cdot p \quad (1)$$

If F represents the holding force measured in grams, A the cross-section of the aperture in cm^2 and p the partial vacuum in the aperture and the suction neck in cm water pressure.

If F is to become as large as possible, then either A or p must be made as large as possible. As represented above A was made as large as possible.

Further the quantity of air which is sucked through an uncovered aperture is directly proportional to the cross-section and $\sqrt{p}$, thus

$$Q = F \cdot A \cdot \sqrt{p} \quad (2)$$

If Q signifies the quantity in cm^3 of air sucked and F a coefficient which must be fixed for every case, A and p have the same significance as in formula 1.

In the interest of efficient working the following requirements are to be fulfilled: great holding force (F in formula 1) and small quantity of air (Q in formula 2).

In the case of a customary suction neck one requirement excludes the other.

The second requirement can be fulfilled:

- (a) by keeping small the coefficient F ,
- (b) by keeping small the suction aperture A ,

(c) by keeping small the under pressure p .

(a) The keeping small of the coefficient F can be obtained if the resistance in the suction aperture is made large, while, for example, each suction aperture is connected by a long tube with the vacuum. This method has the disadvantage of being expensive and rendering the cleaning extremely difficult, when the tubes are choked by mica dust or small thin sheets.

Should the fore F in formula 1, for example, be made four times as great, then if the aperture is enlarged according to (b) there results:

$$5 \quad 4 F = 4 A. p \quad (3)$$

and

$$Q = 4 A. F \sqrt{p} \quad (4)$$

or if according to (c) the under pressure p is increased:

$$10 \quad 4 F = A. 4 p \quad (5)$$

and

$$15 \quad Q = A. F \sqrt{4 p}$$

or

$$15 \quad Q = 2 A. F \sqrt{p} \quad (6).$$

If the equation (4) and (6) are compared it will be seen that it is more advantageous to effect the increase of the holding force by increasing the partial vacuum than by increasing the cross-section, because the size of the ventilator is dependent on the quantity of air to be constantly supplied. Now the idea of the invention is that A in the formulas 1 and 3 and 2 and 6 is made different in size in such a way that the cross-section, in front of which the thin sheets of mica are held, is made larger, while the cross-section for the entrance of the air with uncovered suction aperture is made small.

It is now possible to have the partial vacuum and the suction aperture as large as desired, without the air pump having to be extremely large.

In the drawing different constructional forms according to the idea of the invention are represented. Fig. 1 represents a form in which the base 10 of the suction neck is provided with tubes 11 which are widened at their lower ends 12 in order to obtain a large holding cross-section at their orifices. It will be understood that the upper ends of the tubes 11 communicate with a vacuum. The device may, for example, be in the form of a hollow cylinder, the tubes communicating with the interior of the cylinder in which a vacuum is maintained.

Fig. 2 shows another form. A metal plate 13 is provided with small openings 14. The lower side bears bars or stays 15 which form small boxes providing suction chambers 15^a communicating with the vacuum through the openings 14.

Fig. 3 shows a similar form to that shown in Fig. 2 in which, on the bars 15 is arranged a further metal plate 16 provided with apertures 17 in order to create larger bearing surfaces for the mica sheets.

Fig. 4 shows a form of construction in which the base of the suction neck is provided with small stamped cups 18, each of which is connected with the vacuum by one or more air suction holes 19.

Fig. 5 shows a form of construction similar to Fig. 4, the small cups 20, however, being formed in a thick plate 21, suction holes 22 being provided to connect the cups with the vacuum.

In the constructional forms according to Figs. 1 to 5 a netting 23 of wire, silk or string can be arranged in front of the suction orifices in order to prevent dust or small thin sheets from entering the apparatus.

The suction device can naturally be made in an appropriate form for individual cases, for example, often in the case of mica coating machines, the form of a hollow cylinder can be used to advantage.

What we claim as new and desire to secure by Letters Patent of the United States, is:—

1. A suction device for mica coating machines and the like, comprising a member provided with a plurality of apertures arranged to present a high resistance to the entrance of air when uncovered, said apertures being enlarged at their outer ends to give high holding effect and being mechanically independent of each other so that one or more may be uncovered without opening the adjacent apertures.

2. A suction device for mica coating machines and the like, comprising a member provided with a plurality of relatively large suction openings, each opening being connected with a vacuum through a relatively small aperture whereby a high resistance is offered to the entrance of air when the opening is uncovered, and said openings being spaced apart so that one or more may be uncovered without uncovering the adjacent openings.

3. A suction device comprising a hollow cylinder provided with a plurality of apertures connecting its interior with the outside thereof, said apertures being enlarged at the exterior of said cylinder to give high holding effect and being separated so that one or more may be uncovered without uncovering the adjacent apertures, and means for exhausting the air in said cylinder.

4. A suction device for mica coating machines and the like, comprising a member provided with a plurality of relatively large suction openings, each opening being connected with a vacuum through a relatively small aperture whereby the entrance of air is restricted when the opening is uncovered, and said openings being separated so that one or more may be uncovered without uncovering the adjacent openings, and a screen arranged over said openings.

In witness whereof, we have hereunto set our hands this 23rd day of September, 1925.

RICHARD SPRENGER.
HERMANN CONRADT.
